UNITED STATES PATENT OFFICE.

VERNE L. SULLIVAN, OF ROCKVILLE CENTER, NEW YORK.

RELEASEABLE WINDOW-SUPPORTING DEVICE.

Application filed June 1, 1926. Serial No. 113,002.

This invention relates to improvements in devices for automatically closing windows in the event of rain and has for its object to provide a simple and reliable device of this character and one which may be manufactured at low cost.

There has long been a need for a window closing device for the purpose indicated and various devices more or less complicated have 10 been proposed for the purpose. However, all such devices of which I am aware have necessitated some alteration in the window structure with consequent exposure and have been devised as more or less permanent 15 installations. As permanent installations they have been unsightly and therefore objectionable and none of the proposed devices has met with commercial success.

The present invention aims to provide a 20 device for the purpose indicated which does not require any structural change in any part of the window structure before it can be utilized; which can be put in operative position as easily as a prop or stick; which can be 25 carried from window to window as needs may require and which after it has operated to close the window will fall away from the window into the room ready to be picked up, and, finally, last but least which shall not be 30 an unsightly object.

In accordance with the present invention the device comprises a relatively long prop or stick of sufficient cross-sectional area to support the weight of the window without 35 buckling or bending. The particular form of the prop is of no material consequence though for simplicity of manufacture a rectangular prop or stick is preferred. One end of the stick is perforated to receive a short 40 lever to one end of which is secured a pull rod or wire. This wire near the lower end of the stick is passed through an elongated aperture in the latter and has its terminal bent into the form of a hook. Some distance 45 below the hook terminal and on the same side as the latter there is secured to the stick any suitable hooked element. These hooks are provided to receive and hold suspended between them an element which when wet will 50 immediately tear or split between its ends under a stretching force. The stretching force in the present instance is the weight of the window resting on the free end of the lever to which the wire or pull rod is attached, the device in use being placed beneath 55 the open window with the water destructible

element facing outwardly. In the event of rain if there is any tendency for the water to come into the room, the water destructible element will immediately become wet whereupon inasmuch as it is under tension due to the weight of the window, it will immediately split between its ends and the window will close of its own weight and in closing will dislodge the prop and tend to push it into the 60 room out of the way.

For a more complete understanding of the invention reference is made to the accompanying drawing wherein the preferred form of the invention is shown and the detail description based thereon.

Referring to the drawings:

Fig. 1 is an elevational view of the improved device the water destructible element being shown in position and between the 75 hooks;

Fig. 2 is a side elevation of Fig. 1;

Fig. 3 illustrates the device in place beneath a window;

Fig. 4 is a transverse section through the 80 window structure and showing more fully how the device is positioned to hold the window open; and

Fig. 5 is a view similar to Fig. 4 as regards the window structure but showing the window 85 as having closed following the destruction of the water destructible element, the view further showing the device about to fall into the room.

In the drawings, 10 indicates the body or 90 stick part of the device which may be of any suitable material such as wood, and of sufficient strength to support the weight of the window to be controlled. The length of the stick may be as desired. The stick is apertured as at 12 and hinged within the aperture is a lever 14 to one end of which is secured a rod 15 which near its lower end is bent out of parallelism with itself as indicated at 16 and passed through an elongated aperture 18 in the stick, the lower terminal of the rod being bent to form a hook 20. Secured to the stick below the hook 20 is a second hook 22. The water destructible element is indicated at 24 and as shown is preferably a relatively 95 thin and wide member which is reinforced in any suitable manner at its ends as at 26 to enable it to be held in stretched position between the hooks.

The relative position of the parts when the device is ready to be placed in position is indicated in Fig. 2. It will be observed that the 100

upper face of the lever makes an acute angle with the stick. That this is advantageous will be evident from an inspection of Fig. 4 since it permits the base of the stick to be 5 positioned outwardly of the base strip 28 of the window structure and at the same time affords a supporting surface beneath the window which does not slope downwardly. The weather-exposed side of the window is 10 at the left as viewed in Fig. 4.

Some windows are counterbalanced by weights having cords leading over pulleys. In order to successfully employ my invention the window must tend to close of its own 15 weight. Such windows as are counterbalanced by weights having cords leading over pulleys can be made to close of their own weight in a number of different ways. Thus one of the weights can be rendered non-effective for the time being by elevating the weight and tying a knot in the cord to prevent the weight from moving down when the window is elevated. Or the window can be weighted as by weights 30 supported in brackets 32 affixed to the window sash at any suitable point.

The element 24 is preferably paper of such composition and of such width that it has sufficient tensile strength when dry to withstand the pull exerted between its ends when the window is resting on the free end of the lever 14 but which when wet will sever between its ends under such pull.

The manner of utilizing the device will be 35 more or less evident but may be briefly described as follows:

The prop is made ready by placing a water 40 destructive element 24 on the hooks 20 and 22. The window having been opened, the free end of the lever 14 is placed beneath the window with the element 24 facing outwardly. In the event of rain unaccompanied by wind sufficient to drive the rain in through the open window some rain will usually fall

on the window sill and splash up onto the 45 element 24 and eventually wet it sufficiently to cause it to sever between its ends whereupon the lever 14 being released will of course release the window which will close of its own weight. The window in closing will push 50 the prop aside the lever after release serving as an inclined cam down which the window moves.

What I claim is:

1. A device for holding windows open 55 and allowing them to close under certain conditions comprising a prop adapted to rest upright on the inner side of the windowsill, a lever at the upper end of the prop, one end of said lever adapted for placement beneath the window to be controlled and thereby retain the prop in upright position, means for releasably holding said lever in a given angular position when in window holding position, said means including an element of sufficient tensile strength when dry to prevent turning of the lever when it is supporting the load of the window but of insufficient strength for said purpose when it is wetted with water, whereby in the latter event the 65 weight of the window on the lever will cause the element to sever and cause dislodgment of the prop from beneath the window. 70

2. In combination, an elongated body, a lever pivoted at one end of the body, a rigid pull rod secured to one end of the lever and passing through said body at a point adjacent the lower terminal of the pull rod, a hook affixed to said body below the terminal of the pull rod, the pull rod also having a hook, and means extending between said hooks adapted to withstand a predetermined pull when dry and when wet adapted to sever between its ends under such pull. 75 80

In testimony whereof, I have hereunto affixed my signature this 29 day of May, 1926.

VERNE L. SULLIVAN.
